UNITED STATES PATENT OFFICE.

CHARLES H. BENCKENSTEIN, OF VINTON, LOUISIANA.

LEAKPROOF LOWER OR STANDING VALVE.

1,418,423.

Specification of Letters Patent. Patented June 6, 1922.

Application filed April 4, 1921. Serial No. 458,306.

To all whom it may concern:

Be it known that I, CHARLES H. BENCKENSTEIN, a citizen of the United States, residing at Vinton, in the parish of Calcasieu 5 and State of Louisiana, have invented certain new and useful Improvements in Leak-proof Lower or Standing Valves, of which the following is a full, clear, and exact description thereof.

10 My invention relates to the body of a lower or standing valve used in oil-well pumps and in other deep well pumps and one of the objects of my invention is to provide a valve of this character which is adapted to be used with the present standard ball, seat and cage valve; and also with the standard working barrel and the standard working barrel collar; it being unnecessary to make any changes whatsoever 15 either in the standard ball and cage valve, or in the standard working barrel collar.

Another important feature of my invention resides in the provision of a valve of this character which prevents any leakage 20 of the oil or other liquid between the valve and the working barrel.

Other objects of my invention are to produce a valve of this type which is economical both in manufacture and in use; which may 25 be easily and readily mounted in or removed from the standard working barrel and also one which operates with greater ease and with greater efficiency than similar valves now known.

30 The present standard oil-well or other deep well pump includes a working barrel, having a collar mounted on the lower end thereof, and the interior of this collar is provided with a seat; and engaging this seat is the lower or standing valve, which in standard practice comprises the body to which is attached at the top the usual ball, seat and cage valve, and which body is surrounded by a number of leather washers, 35 the function of which is to prevent any leakage of the oil or other liquid between the valve and the working barrel. Obviously such a construction does not produce a leak-proof connection between the lower valve 40 and the working barrel. It is my purpose to provide a lower valve which is not only absolutely leak-proof, but also which is inexpensive to manufacture and install, as it necessitates no changes whatever in the 45 standard ball, seat and cage valve, the stand-

ard working barrel, or the standard working barrel collar.

With the above and other objects in view I will now proceed to describe one form of my apparatus which accomplishes the above 60 and other objects, reference being had to the accompanying drawings, in which:

Figure 1 is a vertical sectional view of the lower or standing valve; the ball, seat, and cage valve being in elevation.

Figure 2 is a side elevation of the tapering lead washer; and

Figure 3 is a plan view thereof.

Numeral 1 designates the standard working barrel collar or coupling, and which is provided with the usual tapering seat 2. I also show a portion of the working barrel 3 screw-threaded into the top of the working barrel collar, and the perforated pipe 4 screw-threaded into the bottom thereof. 75 All of the foregoing is the standard structure in oil-well or other deep well pumps, and any further description thereof is believed to be unnecessary.

The body of the standing valve consists of a tubular member 5, which may be screw-threaded at both ends, and intermediate of the ends and preferably formed integral with the body is the shoulder 6. The standard ball, seat, and cage valve 7 is adapted 80 to be screw-threaded onto the upper end of the body member.

A lead or other soft metal washer 8 is adapted to be fitted over the body member, under the shoulder 6. The interior of the 90 washer is cylindrical, but the exterior thereof is tapering and is designed to be wedged down into the standard tapering seat 2 of the working barrel collar 1.

A small coupling 9 is screw-threadedly 95 engaged with the lower end of the tubular body member, the coupling abutting the bottom of the seat 2. It will now be evident that by rotating the coupling 9, the body member with its shoulder 6, will be drawn 100 downwardly; and the shoulder engaging the tapering lead washer will force it with a wedging action into the space between the body member and the seat 2, thereby forming an absolutely leak-proof joint between 105 the lower or standing valve and the working barrel of the pump. The coupling 9 is shown of sufficient size for the attachment of a gas anchor should one be desirable.

The ease and rapidity with which the 110

valve is assembled will be apparent from the foregoing description. All that is necessary is to place the soft metal washer on the tubular body member carrying the ball, seat, and cage valve; the working barrel collar is then passed over the body member under the shoulder, and is screwed onto the working barrel. The coupling 9 is now screwed onto the lower end of the body member whereby the shoulder forces the washer into the tapering space between the seat 2 and the body member, forming the desired leak-proof joint between the working barrel and the standing or lower valve.

It will also be apparent that I have produced a leak-proof lower valve, which necessitates no changes whatever in the standard ball, seat and cage valve, the standard working barrel collar, or the standard working barrel; thereby producing a lower valve which is economical both in manufacture and use.

Although I have shown and described what I consider to be the best form of construction of my improved lower or standing valve, it is evident that alterations or changes may be made therein, and I reserve the right to make all such changes as will come within the scope of the appended claims.

Having fully described my invention, what I claim as new and desire to secure by Letters Patent, is:

1. A lower or standing valve including a standard working barrel collar, a standard tapering seat provided in said collar, a tubular body member, a tapering soft metal washer associated therewith, and means for drawing the body member and washer downwardly whereby the latter is wedged into the space between the seat and the body member, said means engaging the under face of the seat.

2. A lower valve for deep well pumps,

including a working barrel collar, a tapering seat provided in said collar, a tubular body member, a tapering lead washer, a shoulder provided on the body member, and means for drawing said body and shoulder downwardly, whereby the washer is wedged into the space between the seat and the body member.

3. A lower valve for deep well pumps, including a working barrel collar, a tapering seat provided in said collar, a tubular body member, a tapering lead washer, a shoulder provided on said body member, and a coupling threadedly engaging the body member and abutting the bottom of said seat, whereby the washer may be wedged into the space between the seat and the body member.

4. A lower valve for deep well pumps, including a working barrel collar, a tapering seat provided in said collar, a tubular body member, a tapering lead washer, a shoulder provided on said body member, a coupling threadedly engaging the body member and abutting the bottom of said seat, whereby the washer may be wedged into the space between the seat and the body member, said coupling being adapted for the attachment of a gas anchor.

5. A valve of the character described including a standard working barrel collar, a standard tapering seat provided in said collar, a tubular body member, a standard ball, seat and cage valve attached to the upper end of the body member, a tapering lead washer, a shoulder provided on said body member, and a coupling threadedly engaging the lower end of the body member and abutting the bottom of said seat, for drawing the body member and shoulder downwardly, whereby the lead washer is wedged into the space between the tapering seat and the body member.

CHARLES H. BENCKENSTEIN.
